United States Patent Office

Des. 178,263
Patented July 10, 1956

178,263

BOX

Mary May Picciano, Lumberville, Pa.

Application April 18, 1955, Serial No. 35,557

Term of patent 3½ years

(Cl. D58—11)

FIG.1.

FIG.4.

FIG.2.

FIG.3.

I claim:

The ornamental design for a box, substantially as shown.
